UNITED STATES PATENT OFFICE.

HENRY R. GILSON, OF BADEN, PENNSYLVANIA, ASSIGNOR TO NATIONAL METAL MOLDING COMPANY, OF PITTSBURGH, PENNSYLVANIA, A CORPORATION OF PENNSYLVANIA.

ARMORED-CABLE CONNECTOR.

1,215,366.

Specification of Letters Patent. Patented Feb. 13, 1917.

Application filed January 28, 1916. Serial No. 74,807.

To all whom it may concern:

Be it known that I, HENRY R. GILSON, residing at Baden, in the county of Beaver and State of Pennsylvania, a citizen of the 5 United States, have invented or discovered certain new and useful Improvements in Armored-Cable Connectors, of which improvement the following is a specification.

The object of my invention is to provide 10 a simple and inexpensive connector for attaching armored cables to electrical fixtures, whereby such attachments may be facilitated, and the cable be securely held in position and against rotation without its being 15 cramped or otherwise prejudicially engaged by the attaching means.

My invention is applicable alike to stationary fixtures, such as outlet boxes secured to a suitable support, and to portable fixtures, such as sockets, attachment plugs, 20 electrically operated tools, etc.

In the accompanying sheet of drawings, forming part of my specification, I have illustrated the preferred embodiment of my 25 invention in its adaptability to the two aforementioned classes of electrical fixtures. Figure 1 is a side elevation of an attachment plug and socket, fastened by means of my improved connector, to the opposite 30 ends of a section of armored cord or cable; Fig. 2 a central vertical sectional view to enlarged scale through the attachment plug and the upper end of the cable; Fig. 3 a plan view of the attachment plug; Fig. 4 a sectional view taken on the line IV—IV 35 Fig. 1; and Fig. 5 a sectional view of an outlet box and a connector similar to that of Figs. 1 and 2 for attaching an armored cable to the box.

40 Armored cables, as contemplated by my invention, include all forms of electrical conductors, cables or cords which are protected by a helical wrapping of metal, whether such metal be in the form of a wire, a curved or bent strip, or in some other 45 form. In the present embodiment of my invention I have shown two conductors 1 and 1^a protected by superimposed helical wrappings of two interlocking curved strips 50 2 and 2^a.

In the practice of my invention I provide a thimble, adapted to receive the end of the armored cable, and having, in its wall adjacent to the cable, a slot or recess adapted 55 to receive an outwardly turned end of the

armor strip and, by such engagement of the strip, effective to prevent the cable from turning, that is rotating upon its longitudinal axis, with relation to the thimble. The cable being thus held against rotation with 60 relation to the thimble, means are provided to hold the cable and thimble against relative longitudinal movement.

In the embodiment of my invention shown in Figs. 1 to 4, inclusive, the cable-receiving thimble is a sleeve 3 formed at one end of an attachment plug 4, the sleeve and the body portion of the plug being preferably formed integrally of suitable moldable insulating material. This sleeve is provided with two slots 5 and 5^a disposed tangentially to its inner bore and extending to its lower edge, each slot receiving an outwardly turned end of one of the two armor strips 2 and 2^a, as clearly indicated. 65 The means for holding the cable against longitudinal movement in the sleeve comprise a screw-threaded bushing 6 engaging the outer face of the sleeve and provided with an inwardly extending flange 7 closing 70 the outer ends of the slots 5 and 5^a and thereby retaining the strip ends within such slots. As will be seen, the conductors 1 and 1^a are, by binding screws 8 and 8^a, electrically connected to the contact fingers 9 and 9^a adapted to be received by the receptacle 18, the construction of which is well known. 75

The lower portion of Fig. 1 shows in elevation the same connector as applied to a lamp socket 10. In attaching the cable to 90 the plug or socket shown in this figure, the bushing 6 is first slipped over the end of the cable. The ends of the armor strips are then bent outwardly and the electrical fixture slipped over the end of the cable, the recesses 95 5 and 5^a thereof receiving the ends of the outwardly turned armor strip. The attachment may then be completed by screwing the bushing 6 upon the sleeve 3.

In the embodiment of my invention shown 100 in Fig. 5, the connector consists of a thimble, made of suitable moldable insulating material, having a central outstanding flange 11 and sleeves 12 and 13 at opposite sides thereof. The wall of the sleeve 12 is provided with armor-receiving slots, and its outer face is threaded to receive a bushing 6 in the same manner as explained with reference to the connector shown in Figs. 1 and 4, inclusive. The sleeve 13 may, as 110

shown, have an outer metal facing 14 molded in the body of the thimble, such facing being threaded to receive a clamping nut 15 for attaching the thimble to an outlet box 16. However, in connectors for some styles of electrical fixtures, the sleeve 13 may be omitted, the insulation material of the thimble then terminating at the inner end of the facing 14. As will be seen, the construction 10 of the thimble is such that the cable armor is insulated from the outlet box. The connector shown in this figure may be attached to the end of a cable in the manner already explained.

15 It will be observed of the connector which I provide that, the cable being held firmly against longitudinal or turning movement with relation to the thimble, no strain may be placed upon the conductors. Furthermore, the cable is engaged in such a manner 20 that the armor is not pressed against the contained conductors, and there is no liability of the insulation of the conductors becoming abraded by the ragged cut ends of 25 the armor strip as is incidental to the use of the usual type of cable holders.

According to the provisions of the patent statutes, I have described the principle and 30 operation of my invention together with constructions which I now consider to represent the best embodiments thereof. However, I desire to have it understood that the 35 constructions shown are only illustrative, and that my invention may be practised by other forms of construction.

I claim as my invention:

1. A connector for an armored cable, comprising a thimble adapted to receive a cable, a slot in the wall of the thimble extending 40 to the edge thereof and adapted to receive an outwardly turned end of an armor strip, and a member secured to said thimble and

Copies of this patent may be obtained for five cents each, by addressing the "Commissioner of Patents, Washington, D. C."

having a portion closing the open edge of said slot.

2. A connector for an armored cable, comprising an externally threaded thimble adapted to receive the end of a cable, a slot in the wall of the thimble extending to the edge thereof and adapted to receive an outwardly turned end of an armor strip, and a bushing having screw threads to engage 45 said thimble and provided with an inwardly turned flange adapted to engage the edge of the outwardly turned armor strip and thereby clamp the cable in said thimble. 55

3. The combination with an armored cable having the end of an armor strip turned outwardly, of a connector surrounding the end of the cable and having a wall provided with a slot extending to the edge thereof, 60 said slot receiving said outwardly turned strip end, and means for retaining said strip end in said slot.

4. The combination with an armored cable having the cut end of an armor strip turned 65 outwardly, of a connector, comprising an externally threaded thimble surrounding the end of the cable, a slot in the wall of the thimble extending to the cable-receiving end 70 thereof and containing said outwardly turned strip end, and a bushing having screw threaded engagement with said threaded thimble and provided with an inwardly extending flange at the cable receiving end of the thimble, said flange closing 75 the end of said slot and thereby securing the cable to the thimble.

In testimony whereof I have hereunto set my hand.

HENRY R. GILSON.
